Des. 185,771
Patented July 28, 1959

185,771

CHILD'S ROCKING SEAT

Thomas Charles Mills, Wheaton, Ill., assignor to Manning Manufacturing Corporation, Chicago, Ill., a corporation of Illinois

Application January 26, 1959, Serial No. 54,306

Term of patent 14 years

(Cl. D15—6)

Fig. 1.

Fig. 2.

Fig. 3.

Fig. 4.

Figure 1 is a perspective view of a child's rocking seat showing my design;

Figure 2 is a side elevational view thereof;

Figure 3 is a top plan view thereof;

Figure 4 is a rear elevational view thereof.

I claim:

The ornamental design for a child's rocking seat, substantially as shown.
